INSULATOR STRUCTURE

Lory E. Stewart and Alvin J. Stewart, Falconer,
N. Y.; Marian Marguerite Stewart and William
F. Stewart, executors of said Lory E. Stewart,
deceased, assignors of one-third to Karl L.
Thielscher, Buffalo, N. Y.

Application December 3, 1938, Serial No. 243,840

4 Claims. (Cl. 174—166)

This invention relates to an insulator structure particularly adapted for use as a three way bracket for telephone, telegraph or for central station of for any wires conveying electrical energy, to be used mainly on telephone poles, although capable of more general use on buildings or other supports.

It is further aimed to provide an insulator structure of the general character mentioned which may be molded with an efficient reinforcement therein which coacts terminally with the pole or other support to prevent turning of the insulator structure and which further coacts with a fastening or securing element.

Another object is to provide an insulator structure wherein torsional strain on the insulator and fastening is minimized.

A further object is to provide such an insulator having spools provided with outwardly extending tapered or equivalent portions to better accommodate angularly disposed wire leads.

Various additional objects and advantages will become apparent from a consideration of the description following taken in connection with accompanying drawing illustrating an operative embodiment.

In said drawing:

Fig. 1 is a view in side elevation showing an improved insulator bracket in connection with a lag screw;

Fig. 2 is a plan view of the insulator bracket;
Fig. 3 is an end elevation of the insulator bracket;

Fig. 4 is a cross section taken on the line 4—4 of Fig. 1;

Fig. 5 is a cross section taken on the line 5—5 of Fig. 1;

Fig. 6 is a longitudinal central section showing the insulator bracket attached to a pole by a bolt;

Fig. 7 is a detail perspective view of the metallic or reinforcing frame;

Fig. 8 is a detail perspective view of a modified form of metallic or reinforcing frame;

Fig. 9 is a front elevation of a modified form of insulator bracket, and

Fig. 10 is detail perspective of the form of metallic or reinforcing frame used in the form of Fig. 9.

Referring specifically to the drawing wherein like reference characters designate like or similar parts throughout the different views, 10 designates an insulator bracket which is usually generally of U-shape and comprising a metallic reinforcing frame and a body 11 of suitable insu-

lation molded thereon while in a plastic state, and for instance, glass, porcelain, and synthetic resin. This structure provides parallel, spaced apart legs or side spools 12 having any desired number of wire or lead-engaging grooves 13. In line with such spools 12 are heads or relatively flat portions 14 adapted to receive hammer blows and from which spools 15 extend inwardly, having any desired number of wire or lead-engaging grooves 16. Such spools 15 are joined by a central enlargement having upper and lower bosses 17 and 18. Ribs or lugs are provided at 19 at the sides of heads 14 and lugs 20 are provided at the tops thereof, to aid in maintaining the wires or leads which are attached thereto, in proper separated relation. The portions 14, spools 15 and the central enlargement constitute a bridge connecting the legs 12.

Reverting to the metallic reinforcing frame within the body 11, and which is generally indicated at A, it may be of the specific form of Fig. 7, that is to be made in similar U-shaped sections 21 placed in contact and welded together, the sections being bulged at 22 to collectively provide an eyelet 23, and a terminal at each side of the frame having a pole-entering spur 24 which projects outwardly beyond the spools 12. Such spurs are preferably tapered and have enlargements or blisters 24a thereon to increase the effectiveness of their engagement in the pole or other support. Said frame A has lugs 14a extending upwardly and terminating flush with surface 14 to receive hammer blows.

In attaching the insulator bracket, the spurs 25 are forced into the pole or other support and, if necessary, blows may be dealt the heads 14 and 14a to drive the spurs into place. These spurs minimize turning and reduce torsion. In addition, a fastening as at 25 is passed through the bore of the bosses 17 and 18 and the eyelet 23. The fastening 25 in Fig. 1 is specifically shown as a lag screw, adapted to engage the same pole or other support as the spurs 24. Obviously any other suitable fastening may be substituted for the lag screw 25.

The legs or side members 12 at inner corners or edges of their attaching ends may be bevelled or otherwise cut to better fit a pole when the bracket is installed horizontally.

The different spools 12 and 15 taper or are reduced in an outward direction as shown to better accommodate angular leads or wires.

A spool 26 of insulation like the body 11 loosely surrounds the fastening 25 and is sufficiently

short as not to be clamped against turning when the bracket structure is fastened in place.

As a result, the insulator bracket will accommodate the leads or wires in efficient relation, the same being fastened to the grooves of the spools 12 and 15 with the loose sleeve or spool 26 minimizing torsion or tendencies to turn imparted by wires in contact therewith. Should the insulation fracture, there will still be the interengaged frame A and fastening 25 to prevent detachment of the leads or wires.

Various changes may be resorted to provided they fall within the spirit and scope of the invention. For instance in Fig. 6, the insulator bracket structure utilizes a fastening or securing member 27 in the form of a detachable bolt, in lieu of the lag screw 25.

In Fig. 8, a modified form of reinforcing or metallic frame is shown which may be used in place of that at A, in this instance consisting of a metallic rod bent to provide an eyelet 28 to function like that at 23 and having the free ends of its legs provided with spurs 29 to function like those at 24, and the upper ends provided with hammer heads 28a to function like those at 14a.

In the further modified form of Figs. 9 and 10, a body 11a of insulation like that at A, is shaped like the body A with the addition of a cross piece 30. Any suitable fastening like that at 25 or 27 secures the structure in place, passing through eyelets 31 and 32 in a metallic or reinforcing frame 33 and a spool 26a like that at 26. Embedded in the cross piece 30 abutting frame 33 are metallic pins 34 having spurs 34a thereon like those at 24.

We claim as our invention:

1. An insulator structure comprising a rigid body of insulation generally of U-shape providing spaced legs adapted at their free ends to contact a support, a reinforcing frame of U-shape embedded within the body, a separate fastening element passing through the frame intermediate said legs and extending beyond the free ends of the legs for attachment to the support abutted

5 by the free ends of the legs, said insulator legs being in the form of spools arranged to be surrounded by wire terminals, said spools being reduced in dimension in outward direction to accommodate angularly disposed leads.

2. An insulator structure comprising a rigid body of insulation including substantially parallel side spools, one end of each side spool being free, heads at the other ends of said spools, lugs 10 on said heads to aid in maintaining wires separated, said free ends being disposed to abut a support, spools intermediate said heads, boss means joining the second mentioned spools having a bore, and a fastening disposed in said bore extending beyond the free ends of the side spools for attachment to the support.

3. An insulator structure according to claim 2 having a metallic reinforcing frame embedded therein extending substantially throughout the side spools and across the boss means, said frame having an eyelet registering with said bore and through which the fastening passes, and the terminals of the frame extending beyond the free ends of the side spools to prevent turning of the insulator structure on the fastening.

4. An insulator structure comprising a rigid body of insulation having a portion generally of U-shape providing spaced legs in the form of spools arranged to be surrounded by wire terminals and providing a bridge connecting adjacent ends of the legs, a metallic frame embedded within the body, said bridge and frame having openings extending completely therethrough located between and approximately parallel to the legs, 30 a fastening member passing through said openings having its free end at the side of the bridge opposite to the legs and its attaching end located beyond the other ends of the legs, a spool on the fastening member between said attaching end and bridge, and means extending from the frame and beyond the other ends of the legs to engage a support to prevent turning of the structure about said fastening member.
